PHONOGRAPH DISC RECORD HOLDING RACK

Alfred D. Johnson, Box 110-A, R.F.D. 2,
Lynchburg, Va.

Filed June 14, 1965, Ser. No. 85,702

Term of patent 14 years

(Cl. D33—3)

FIGURE 1 is a perspective view of a phonograph disc record holding rack embodying my new design;

FIG. 2 is a side elevational view; and

FIG. 3 is an end elevational view.

The essential feature of the new design consists of a base board of elongated shape having at each end a convexly curved outer edge of approximately 270° of arc, merging inwardly into a relatively narrow portion formed by two parallel straight edges, with an upright post mounted at the center of curvature of each of said arcs, the radii of curvature of said two arcs being co-equal and bearing such relation to the length of said parallel straight edges that disc records impaled on said posts of a size only slightly overlapping said curved outer edges will have their adjacent inner edges spaced apart centrally of the base board, as shown.

I claim:

The ornamental design for a phonograph disc record holding rack, as shown and described.
